AUTOMATIC STEAM CONTROL AND DIFFERENTIAL FOR PAPER MACHINES.

Application filed January 17, 1925. Serial No. 3,106.

This invention pertains to a differential pressure control valve for maintaining a given differential pressure between the blowing through section and the condensing section of a paper drying machine.

It is well known that it is essential to create a difference of steam pressure between the two sections of a drying machine so as to maintain a rapid circulation of steam through the dryers. The so-called blowing through system gives rapid circulation providing a sufficient pressure is used and the system installed does not equalize. Rapid circulation of the steam through the machine has the advantage of a complete removal of air and condensation at all times, which keeps the dryers as hot as possible and allows for maximum production. The difficulty heretofore has been in maintaining sufficient differential of pressure between the two sections to cause a rapid circulation of steam therethrough and thereby removing the air and condensation. If the pressure is too low, it can not be operated as a rapid circulating system. Heretofore, a greater differential of pressure has been obtained by creating a vacuum by employing jet condensers. A spray of cold water maintains a vacuum by condensing the steam. To maintain a vacuum in this manner requires substantially twenty-five times as much water as steam condensed and there is accordingly a large loss in this method when the excess hot water goes to the sewer, which is usually the case.

The principal object of this invention is to provide a valve for automatically maintaining a given differential of pressure between the two sections which makes a positive flow of steam through the main section. By means of this device, there will be no steam blowing through, and no cold water or spray required to consume steam in order to maintain a vacuum. While a vacuum pump is employed, the exhaust in the pump is piped to the steam header so that there is no loss from operating the vacuum pump. This permits of a positive vacuum of ten to fifteen inches without the use of any cooling water, thereby giving perfectly drained dryers at a minimum cost, and is accomplished by means of a valve located between the steam headers of the two sections for controlling the admission of steam from the header of the blowing through section to the header of the condensing section. It is desirable that

the steam pressure in the latter section be less than that of the blowing through section. This differential is positively controlled by a valve controlled device which will hereinafter be more fully described and forms the subject matter of this invention.

The full nature of the invention will be understood from the accompanying drawings and the following description and claims:

In the drawings, Figure 1 is a diagrammatic illustration of a paper drying system employing the differential pressure control valve. Fig. 2 is a perspective view of the control valve. Fig. 3 is an enlarged view showing the control valve with a portion thereof in central vertical cross section.

In the drawings there is illustrated a paper drying machine mounted upon the floor 10 and employing a frame structure 11, 12 and 13 upon which a paper feeding roll 14 is mounted so that the paper 15 may pass thereabout over the drying rolls 16 and rolls 17. The drying rolls 16 are embodied in the blowing through section of the machine, indicated by the group "A", whereas the rolls 17 are embodied in the condensing section of the machine, indicated by the group "B".

The steam plant, headers and control valves are principally positioned below the floor 10. Said steam is supplied by pipe 18 having an automatically-controlled exhaust steam admission valve 19 to the steam header 20 of group "A". Communicating with the steam header 20 there is a plurality of pipes 21 communicating with the respective drying cylinders or rolls 16 so that the steam passes therethrough and returns through the pipes 22 to the return header 23. The admission of steam through the valve 19 is controlled in the usual manner by suitable valve-controlled means which will not be described specifically herein, as forming no part of this invention. The return header 23 is in communication through pipe 123 with a receiving trap 24 communicating through a valve 25 with a pipe 26^a leading to a vacuum pump, not shown.

The steam passes from the return header 23 of the "A" group through the trap 24 by pipe 124 to the header 26 of the "B" group. Condensation water is drained from trap 24 through pipe 125 with valve 25 and pipe 26^a by a vacuum pump not shown. The header 26 of the "B" group is also in auto-

matically controlled communication with the header 20 of the "A" group through a differential pressure valve 57 in the valve casing 27 which connects directly the two 5 ends of the headers 20 and 26 that are in alinement with each other. The condensing section rolls 17 receive steam from the header 26 through pipes 28 and discharge the same through the pipes 29 to the return header 30 which communicates directly with the vacuum pump line 26a.

In order to maintain at all times a given difference of pressure between the header 20 and the header 26, whereby there will be 15 a rapid circulation of steam between sections "A" and "B", the valve in the valve casing 27 is automatically controlled by the relative steam pressures existing in the respective headers 20 and 26. The header 20 is connected through a pipe 31 with the lower side 20 of a diaphragm housing 32, said pipe being controlled by a valve 33. The header 26 is connected through a pipe 34 with the top of the diaphragm housing.

25 Positioned in the housing there is a suitable diaphragm 35 separating the top and bottom of the housing and operatively connected by a plunger 36 with a disk 37 which in turn operates a rod 38. The rod 38 extends upwardly through a suitable frame 39 terminating in a pilot valve housing 40 and having positioned on the end thereof a valve member 41 for opening and closing the pilot valve. Communicating with the pilot valve 35 housing 40 there is a conduit 42 leading from a source of pressure in the form of either liquid, air or gas. Connected with the other side of the valve housing 40 there is a pipe 43 communicating with the lower end of a 40 piston cylinder 44. Mounted in the cylinder 44 there is a piston 45 connected with the piston rod 46 upon which may be mounted the counterbalance weights 47. The upper end of the piston rod 46 is connected 45 with a chain 48 adapted to pass over the pulleys 49 which are mounted upon a bracket 50, the other end of the chain being connected with a valve actuating lever 51.

55 Slidably mounted upon the lever 51 there is a weight 52 for normally maintaining said lever in lower position. The lever 51 extends through a guide arm 53 and is pivoted at 54 to a valve stem 55, and the lever is pivotally connected through a link 56 with the valve casing 27. The valve stem 55 extends into the valve casing 27 and has secured thereon a valve member 57 for opening and closing said valve.

For counterbalancing the movement of the 60 diaphragm and pilot valve there is provided a compression spring 58 positioned between the disk 37, and a collar mounted on the frame 39, said spring surrounding the rod 38. Pivoted to said rod within the frame 65 39 at 59 there is a lever 60 having variable

weights 61 suspended from one end thereof, the other end of said lever being pivotally connected to said frame through a link 62.

From the foregoing it will be observed that in operation, and assuming that it is 70 desired to maintain a differential of pressure between the headers 20 and 26 of ten pounds pressure, the proper weight 61 is placed on the arm 60. The downward pressure exerted thereby on the rod 38 against the diaphragm 75 35 will act as an auxiliary pressure to the steam pressure passing through the pipes 34 from the header 26, in this instance such auxiliary pressure being the equivalent of ten pounds. The differential pressure of 80 ten pounds, in addition to the pressure from the header 26, will accordingly neutralize the pressure exerted from the header 20 through the pipe 31, which will maintain the pilot valve 41 in closed position, which, in 85 turn, will prevent the operation of the piston 45 and accordingly the valve member 57, whereby the valve 57 will be closed. In order to maintain such differential of pressure, upon a decrease of pressure occurring 90 in the header 26 due to the closure of the valve 57, the diaphragm 35 will be forced upwardly by the pressure through the pipe 31. This will open the pilot valve and cause pressure to be exerted in the pump for moving the piston 45 upwardly, permitting the lowering of the lever 51, which will open the valve 57. Steam will pass therethrough into the header 26 in which the pressure will be raised sufficiently to cause the diaphragm 95 35 to be forced downwardly, which will close the pilot valve 41, so that the piston 45 may be forced downwardly by the weights 47 and the lever 51 accordingly elevated, so as to close the valve 57. The lowering of the 100 piston 45 is permitted by the escape of fluid through the pet cock 63, which remains slightly open. This control of the valve 57 will thereby cause any variation from the desired differential of pressure to either open 105 or close said valve and accordingly maintain such differential substantially constant.

110 Through the automatic control of the valve 57 and by manipulation of the weight 61, said valve will maintain a given difference in pressure between the sections of the paper machine headers, with any variations in the drying pressure. This difference in pressure between the two sections provides a rapid circulation of steam through the 115 dryers of the machine, whereby the dryers are perfectly drained.

120 The invention claimed is:

1. The combination with a paper drying machine having a blowing-through section, a condensing section, a steam supply header and return header for each of said sections, a connection between the return header of the blowing-through section and the steam supply header of the condensing section, and 125 130

- a connection between the steam supply headers of the two sections with a differential valve mechanism therein which is influenced by pressures in both of said steam headers so that the desired difference in pressures in said headers may be automatically maintained regardless of the variations in pressure in the steam supply header in the blowing-through section.
2. The combination with a paper drying machine having a blowing-through section, a condensing section, a steam supply header and return header for each of said sections, a steam trap connected with the return header of the blowing-through section and the steam supply header of the condensing section, means for exhausting the condensation water from said trap, and a connection between the steam supply headers of the two sections with a differential valve mechanism therein which is influenced by pressures in both of said steam headers so that the desired difference in pressures in said headers may be automatically maintained regardless of the variations in pressure in the steam supply header in the blowing-through section.
3. The combination with a paper drying machine having a blowing-through section, a condensing section, a steam supply header and return header for each of said sections, a continuous connection between the return header of the blowing-through section and the steam supply header of the condensing section, a direct connection between the steam supply headers of both of said sections, a differential valve for controlling said last mentioned connection, a pilot valve for controlling the operation of said differential valve, and means for controlling the pilot valve by the opposing influence of the steam pressures in both of said steam supply headers.
4. The combination with a paper drying machine having a blowing-through section, a condensing section, a steam supply header and return header for each of said sections, a continuous connection between the return header of the blowing-through section and the steam supply header of the condensing section, a direct connection between the steam supply headers of both the said sections, a differential valve for controlling said last mentioned connection, a pilot valve for controlling the operation of said differential valve, means for supplying the steam pressure in the steam supply header of the blowing-through section for opening the pilot valve to cause the opening of the differential valve, means for supplying the steam pressure in the steam supply header to the condensing section tending to close the pilot valve, and a weight also tending to close the pilot valve and so as to maintain the desired difference in pressures in said headers at all times.
5. The combination with a paper drying machine having a blowing-through section, a condensing section, a steam supply header and return header for each of said sections, a continuous connection between the return header of the blowing-through section and the steam supply header of the condensing section, a direct connection between the steam supply headers of both the said sections, a differential valve for controlling said last mentioned connection, a pilot valve for controlling the operation of the differential valve, a diaphragm for controlling the operation of the pilot valve, means for supplying steam pressure in the steam supply header of the blowing-through section against one side of the diaphragm for opening the pilot valve and causing the opening of the differential valve, means for applying steam pressure in the steam supply header of the condensing section against the opposite side of the diaphragm and tending to close the pilot valve, and a weighted lever acting on said pilot valve in aid of the steam pressure in the header of the condensing section for closing the pilot valve and maintaining the desired difference in pressures in said headers regardless of the variations in pressure in the steam supply header in the blowing-through section.
6. The combination with a paper drying machine having a blowing through section, a condensing section, and a steam header for each of said sections, of means for maintaining a given differential of pressure between said headers, comprising a valve through which the steam must pass from one header to the other, a piston operably connected with said valve for opening and closing the same, a pilot valve communicating with said piston for actuating the same when opened, means for actuating said piston when said pilot valve is closed, a diaphragm having one side thereof effected by the pressure from one header and the other side effected by the pressure from the other header, said diaphragm being operatively connected with said pilot valve, and means connected with said diaphragm for exerting an auxiliary pressure thereon and thereby maintaining a differential of pressure between said headers.

In witness whereof, I have hereunto affixed my signature.

COLE STICKLE.
